RAILROAD SWITCH

George A. Swazey, Milo, Maine

Application June 19, 1950, Serial No. 169,010

1 Claim. (Cl. 246—446)

1

This invention relates to railroad switches.

An object of this invention is to provide an improved railroad switch which is so constructed as to eliminate any possibility of derailment and to provide switching rails which are substantially normal in size as to the heads thereof rather than being formed as points.

Another object of this invention is to provide a railroad switch structure adapted for interposing in a main line and a pair of oppositely extending sidings, the structure being so constructed both sidings may be served from a single switch structure.

A further object of this invention is to provide a switch structure of this kind which is so constructed that it will not become clogged or inoperative during snow or icy weather.

With the above and other objects in view, my invention consists in the arrangement, combination and details of construction disclosed in the drawings and specification, and then more particularly pointed out in the appended claim.

In the drawings:

Figure 1 is a plan view of a railroad switch structure constructed according to an embodiment of this invention.

Figure 2 is a fragmentary sectional view taken on the line 2—2 of Figure 1.

Figure 3 is a fragmentary sectional view taken on the line 3—3 of Figure 1.

Figure 4 is a fragmentary sectional view taken on the line 4—4 of Figure 1.

Figure 5 is a fragmentary sectional view taken on the line 5—5 of Figure 1.

Figure 6 is a fragmentary sectional view taken on the line 6—6 of Figure 1.

Figure 7 is a fragmentary sectional view taken on the line 7—7 of Figure 2.

Referring to the drawings, the numerals 10 and 11 designate a pair of main line rails, and the numerals 12 and 13 designate a pair of siding rails. A second pair of side rails 14 are disposed oppositely from the siding rails 12 and 13 extending in the opposite direction from rails 12 and 13.

A switch structure constructed according to an embodiment of this invention is interposed in the main line rails 10 and 11 and in the siding rails 12, 13, and 14. The switch structure embodies a pair of base plates 15 which are each provided with a pair of upstanding and relatively thick webs 16 and 17. The web 16 is adapted to be normally disposed in alignment with the main line rail 10, and the web 17 is adapted to be normally disposed in alignment with siding rail 12 when the switch structure is disposed in a position to

2

permit the train and cars to move over the main line. The web 17 is the siding web and is longitudinally curved.

A relatively short straight rail section 18 is carried by the base 15 at one end thereof being in alignment with the main line rail 10, and a second relatively short fixed rail section 19 is disposed at the opposite end of the base 15 being also in alignment with main line rail 10. A relatively short fixed rail member 20 is carried by the base 15 in offset relation to rail section 18 and is adapted to abut the adjacent end of the siding rail 12. A second side rail section 21 is disposed at the opposite end of the base 15 and is adapted to abut against the second siding rail 14.

The two base members 15 are connected together in parallel relation by means of a plurality of spaced apart tie bars 22 which are secured at the opposite ends thereof to the base members 15 by fastening members 23. A rail head carrier constructed in the form of an elongated plate 24 slidably engages over the pair of wide webs 16 and 17 which constitute guides for the plate or carrier 24, and the carrier 24 has secured through a main line rail head 25 and a siding rail head 26. The siding rail head 26 is longitudinally curved so that when the main line rail head 25 is in alignment with the main line 10, the siding rail head 26 will be disposed in abutting and aligning relation with respect to the siding rail sections 20 and 21.

The carrier plate 24 at one end thereof is formed with an endwise projecting tongue or pivot member 27, and the fixed rail sections 18 and 20 which are formed integral with the guides 16 and 17 are provided with slots 28 within which the carrier 24 slidably engages, the upper side of the slot being disposed in substantial alignment with the lower side of the rail heads of the fixed rail sections 18 and 20. As shown in Figure 7, the tongue or pivot 27 is rounded as indicated at 27a so that the carrier 24 may be swung clockwise as indicated by arrow 27b, from a position wherein the main rails are in alignment and the siding rails are also in alignment, to a position wherein the opposite ends of the siding rails will align with the main rails, as shown in dotted lines in Figure 1. The fixed rails 19 and 21 also have slots 29 in the webs thereof within which the adjacent ends of the carriers 24 are adapted to slidably engage. The adjacent end of the rail section 18 has the head thereof cut on a bevel as indicated at 30, and the adjacent end of the rail head 25 is undercut as at 31 so as to be parallel with the bevel 30. At the opposite end the head of the rail section

19 is cut on a bevel as indicated at 32, and the adjacent end of the rail head 25 is undercut as at 33 so as to be parallel with the bevel 32. The siding rail head 26 and the siding rail members 20 and 21 are undercut in a manner similar to that shown in Figure 2 with respect to the fixed rails 18 and 19, and the main rail head 25. The relatively thick webs 16 and 17 which form guides for the carrier 24 are extended at the opposite ends thereof to provide reinforcing webs 34 formed integral with the webs with the fixed rail sections 18, 19, 20, and 21. The swinging ends of the carriers 24 are limited in one direction by means of stop members or lugs 35 which are carried by blocks 36 fixed in any suitable manner to the guides 17.

The two carriers 24 are connected together at the ends thereof opposite from the pivot members 27 by means of a tie bar 37 which engages beneath the plates 15. The tie bar 37 has fixed thereto a pair of upwardly offset lugs 37 formed with bases 38 secured by fastening means 39 to the tie bar 37.

A pivot member 40 extends through a tongue or lug 41 projecting from one edge of plate or carrier 24 and is secured in the lug 37. A second pair of lugs or stop members 42 are disposed oppositely from the lugs 37 being formed with bases 43 secured by fastening means 44 to the tie bar 37. The lugs 34 confront the guide members or webs 16 and are adapted to abut against the web 16 when carrier 24 is disposed in a position with the main line head 25 aligning with the main line rail 10. A pair of pins 45 are extended through the lugs 41 and are adapted upon swinging of the carrier 24 to a switching position to abut against the web or guide 17. A lug 46 is fixed to the web of each rail section 21 beneath the head thereof and projecting outwardly from the slot 46 so as to provide an additional bearing surface engageable with the adjacent end of the carrier 24. The carrier 24 has projecting from one edge thereof a relatively long lug 47, and a stop member 48 is extended through the lug 47 for engagement with the guide 17 when the carrier is swung to a switching position.

The lug 47 is positioned intermediate the length of the carrier 24 so that this carrier will be stopped in its swinging movement towards switching position by two or more stop members.

In the use and operation of this switch structure the connected together base members 15 are interposed in the main line rails 10 and between the siding rails 12, 13, and 14. The tie bar 37 projects laterally from one of the base members 15 and is adapted to be connected to a suitable operator at one side of the rail structure. When the switch is disposed in a position as shown in full lines in Figure 1 the cars and engine will move along the main line 10. Where it is desired to switch the cars and engine onto siding rails 12 and 13, as an example, the cars and engine are moved to the left as viewed in Figure 1, and when the last car has passed the ends of the rail heads 25 and 26, the carriers 24 may be shifted to the dotted line position shown in Figure 1.

The cars and engine may then be moved to the right, and at this time the switching rail heads 26 will be disposed in alignment or abutting relation with respect to the fixed rail members 19.

The cars and engine will thereupon move over siding rail head 26 and onto siding rails 12 and 13. In the event it is desired to shift the cars to the oppositely disposed siding rails 14 the switch is shifted to its main line position shown in full lines in Figure 1, and the cars are then moved to the left. The cars will move over the siding rail heads 26 which at this time are disposed in abutting and aligning position with respect to rail members 21 and 14.

A switch structure constructed according to an embodiment of this invention will eliminate the thin switch points at present in use which frequently cause derailments. Furthermore, in view of the fact that the carriers 24 are slideable on the guide webs 16 and 17 in a horizontal position, these carriers will not be held against movement by accumulation of ice or the like so that the switch structure will be operative in a safe manner under all weather conditions.

What is claimed is:

A railroad switch for interposing in a main rail line and between a pair of oppositely extending sidings comprising a pair of base members each formed of a base plate and a pair of spaced apart upstanding webs fixed to said plate, a pair of stub rails extending from the ends of said webs and fixed to said plate, one member of each pair of stub rails aligning with the main rail and the other member of said pair of stub rails aligning with an adjacent siding rail, a pair of carriers slidably engaging on the upper edges of said webs between said stub rails, a pair of spaced substantially parallel rail heads fixed to each carrier, said rail heads in one position of said carriers aligning said stub rails, each stub rail having an outwardly projecting slot in the inner end thereof within which said carrier slidably engages, means pivotally mounting said carriers at one end thereof between adjacent pairs of stub rails, a carrier shifting member engaging beneath said base plate, and means pivotally securing said shifting member to said carriers at the ends thereof opposite from said pivot means.

GEORGE A. SWAZEY.
